UNITED STATES PATENT OFFICE.

HENRY H. GOVE, OF BIDDEFORD, MAINE.

FLUSHING DEVICE.

1,216,797.

Specification of Letters Patent. Patented Feb. 20, 1917.

Application filed March 12, 1910, Serial No. 548,846. Renewed July 21, 1915. Serial No. 41,190.

To all whom it may concern:

Be it known that I, HENRY H. GOVE, of Biddeford, in the county of York and State of Maine, have invented certain new and useful Improvements in Flushing Devices, of which the following is a specification.

This invention relates to flushing tanks, and more particularly to flushing tanks provided with a siphon discharge.

10 The object of the invention is to improve the construction and mode of operation of flushing tanks of this character as heretofore constructed.

It has been proposed heretofore to provide 15 a flushing tank with a siphon discharge to eliminate the customary valve in the bottom of the tank. This is desirable for it is difficult to keep the valve tight, owing to the collection of sediment in the bottom of the 20 tank, and the consequent leakage of the water often results in a large waste of water and expense, especially where meters are in use. The devices heretofore employed have included a piston of comparatively large 25 area arranged to lift the water and force it through a comparatively small discharge pipe to start the siphon into action. With this construction the operation of raising the water sufficiently to start the siphon was 30 comparatively slow, and considerable force was required to raise the piston.

Accordingly a feature of the present invention contemplates the provision of a siphon tube which is of substantially uniform cross-section throughout the short leg and over the bend, beyond the bend, gradually becoming contracted until the discharge pipe is reached. A paddle or vane is pivotally mounted near the bottom of the short 40 leg of the siphon, and provided with means whereby it may be manually tilted. With this construction it has been found that the water can be quickly and easily raised to start the siphon into action, and as the water 45 flows down through the contracted portion it is caused to fill the discharge pipe and thus form a seal which insures the action of the siphon until the water in the tank recedes to such a level that the siphon stream 50 is broken, whereupon the vane returns to its original position.

A further feature of the invention contemplates the provision of improved means for insuring an afterflow or limited supply of 55 water to the apparatus which has been flushed, after the flushing action has been

completed. Accordingly, one or more chambers or receptacles are provided adjacent to the discharge pipe of the siphon with an inlet and an outlet opening, the inlet opening 60 being larger than the outlet opening. By this construction, during the flushing operation, a portion of the water being discharged through the siphon enters the chamber or chambers through the inlet opening at a 65 greater rate than it is discharged through the outlet, thus leaving a quantity of water in said chamber at the end of the flushing operation, which water then discharges slowly through the outlet, and is conveyed to 70 the apparatus which is flushed, but its volume and speed are so small that it has no flushing action.

A further feature of the invention contemplates the provision of a simple construction 75 which enables the vane or paddle to be readily removed from or inserted in position in the siphon or used with its actuating arm on either side.

Still another feature consists in arranging 80 the vane or paddle in its casing so that when the siphon is broken the column of water remaining in the short leg above the vane will act to force the vane back to its initial position, thus obviating the necessity 85 of counter weights or springs and insuring a certain return of the vane.

Other features of the invention will be referred to in connection with the specific description of the illustrated embodiment of 90 the invention. The several features of the invention will be clearly understood from an inspection of the accompanying drawing and the following detailed description of the construction shown therein.

In the accompanying drawing Figure 1 is a perspective view of the tank and siphon, with a portion of the tank broken away; Fig. 2 is a fragmentary sectional elevation of the siphon and tank, showing the siphon 100 in action; Fig. 3 is a perspective view, partly in section, of a modified form of siphon; and Fig. 4 is a fragmentary detail view.

As shown in the accompanying drawing 105 the device comprises a rectangular tank 1, of any usual or well known construction, upon the bottom 2, of which the siphon is mounted. The short leg of the siphon comprises a metal conduit 4 which is rectangular in cross-section, and provided with a flaring lower extremity 6. The end walls 110

of the conduit 4 are substantially parallel and their lower edges are provided with integral strips or tongues 8, which are bent into the form of semi-circles and which act 5 as bearings for a rod 10, to which a paddle or vane 12 is attached. The housing of the flaring lower extremity 6 of the conduit 4 is formed with an inclined wall, the lower edge of which is bent to conform to the 10 rod 10 and also to form a support or bearing for the latter. The ends of the tongues 8 are spaced a short distance from the lower edges of the walls of the conduit to enable the paddle 12 to be inserted or removed 15 therefrom, as will hereinafter be described. The rod 10 is bent to form a crank-arm 18, and is provided near its end with a hole through which a wire 22 passes, said wire being formed into a hook 24 at its lower 20 end. The wire may be connected to a lever (not shown) provided with means by which it may be manually operated to tilt the paddle or vane 12 upwardly. The hole in the crank-arm 18 is made substantially vertical 25 and sufficiently large to enable the wire 22 to slide freely through the same and to return to its normal position when released after the vane has been raised manually, without causing the vane to return. The 30 length of the inclined wall of the portion 6 is slightly less than the length of the vane 12 so that when the latter is swung into its upper position its outer end will project a short distance beyond the vertical wall of 35 the conduit 4. The inner side wall 26 of the housing is curved to fit the edge of the vane 12 as it is tilted. Pivotaly mounted on each end wall of the housing of the lower extremity 6 is a hook 28 against which the 40 vane 12 is adapted to rest when in its lower-most position. When in this position the vane is prevented from sliding endwise out of the conduit by a projection 30 formed on the lower edge of each end wall just 45 above the end of the tongue. The vane, in its initial position, projects slightly below the lower edge of the siphon, thus affording a space through which the water 50 may enter the short leg. In order to remove the vane 12 from the siphon the hook 28 is swung out of the path of the vane, which may then be tilted low enough to pass through the slot formed between the projection 30 and the end of the tongue 8. In 55 this connection it should be noted that the vane may be inserted from either side of the conduit 4 by being inverted and the crank arm 18 may thus be located on either side as desired.

60 The upper end of the siphon is in the form of an inverted U-shaped conduit or return bend 32 of the same cross-section as the short leg 4, which then merges into a funnel or hopper-shaped portion 34 which is connected to a discharge pipe 36, these

together forming the long leg of the siphon. It will be seen that the short leg and bend of the siphon are of greater capacity than the long leg and that there is no constricted passage through which the water must be forced in starting the siphon, as in those devices where the capacity of the siphon passage is reduced upon the short side of the bend. In the present device, on the contrary, the constriction occurs below the bend 75 on the long side, at which point the water is falling under the influence of gravity. On this account the operation of the vane may be easily effected for starting the siphon action and the friction of the water 80 in the siphon at the time of starting is reduced to a minimum. The funnel portion 34 is made relatively short and of limited capacity so that it will be quickly filled and the siphon action consequently commenced. On this account the discharge pipe 36 joins the funnel portion at a point 85 above the foot of the short leg. The pipe 36 is provided with collars 38 and a nut 40 by means of which it is secured to the bottom 2 of the tank to support the siphon within the tank. It will be understood that the tank may be provided with a ball-cock or any other suitable means for controlling the supply of water thereto. 95

The operation of the device described above is as follows:

The water will stand in the short leg of the siphon at the same height as in the tank, there being no water in the long leg. 100 When the wire 22 is raised the vane is tilted upwardly, lifting the water above the same so that it flows over the bend into the funnel-shaped portion 34. Here the water converges into the pipe 36, thus filling the latter completely as shown in Fig. 2, and making a seal to insure the continued action of the siphon. When the current through the siphon has once been started the vane 12 is held by the rush of water in a raised position as shown in Fig. 2 in which position a 105 free passage for the water is afforded. By this arrangement the necessity of a valve in the vane is obviated and the construction of the device thereby greatly simplified. When 110 the water in the tank recedes to such a level that the siphon stream is broken, the flow of water through the siphon ceases, and the column of water remaining in the short leg above the vane flows back impinging on the 115 end of the vane which projects into the conduit 4 and operating to force the vane down to its normal position. It will be noted that the vane 12 is free to swing below the bottom of the casing for a short distance before it encounters the stops 28. The vane, on its return movement will strike the surface of the water remaining in the tank at the end of the flushing operation, thus being cushioned. It will, therefore, be more quiet 120 125 130

in action than if it struck the stops 28 directly.

From the foregoing description it will be seen that my improved flushing device presents no opportunity for leakage since it requires no submerged valves except the vane 12 past which there is normally no tendency to leakage.

In Fig. 3 a modification is shown in which the siphon is of substantially the same construction as that described above, but in addition thereto means are provided for insuring an afterflow or limited supply of water to the apparatus which has been flushed, after the flushing action has ceased. Below the funnel-shaped portion 50 are one or more chambers or receptacles 52, having a supply inlet 54, formed in the wall of the funnel, and a discharge opening 56, of smaller area than the supply inlet communicating with the discharge pipe 58. Thus during the flushing operation of the siphon a portion of the water passes through each supply inlet 54 into the corresponding chamber 52, and the inlet being of greater area than the discharge opening 56, enables water to accumulate in each chamber 52. When the flushing has ceased, the water in the chamber 52 continues to flow through the opening 58, but is of such a small volume that it does not cause any flushing action.

While I have illustrated and described a preferred embodiment of the invention, I am aware that many modifications can be made therein by any person skilled in the art without departing from the scope of the invention as expressed in the claims. Therefore I do not wish to be limited to all the details of construction shown and described, but what I claim is:—

1. A flushing tank having, in combination, a siphon having a straight portion and a flaring portion in its short leg, a vane pivoted at one side of said flaring portion with its free end arranged to swing in the lower part of the straight portion, and an arm whereby the vane may be turned about its pivot to start the action of the siphon, the end of said vane extending obliquely into

the straight portion of the short leg during the action of the siphon whereby it may receive a reseating impulse at the end of the action of the siphon.

2. In a flushing tank, the combination of the tank proper, a siphon mounted within the tank and having a funnel-shaped portion, a discharge pipe communicating with said funnel-shaped portion, means for raising water to start the siphon into action, and a plurality of receptacles mounted on opposite sides of said discharge pipe, each having an inlet opening communicating with said funnel-shaped portion and an outlet opening communicating with said discharge pipe, said inlet opening being of larger area than said outlet opening, substantially as described.

3. In apparatus of the class described, the combination with a tank, of a siphon within the tank having its long leg extending downwardly from the tank, a housing having an outlet opening into the short leg of the siphon, said housing constituting a portion of the short leg and having a curved wall and an inclined straight wall, said walls diverging downwardly from the outlet, the bottom of said housing constituting an inlet, a charging vane fulcrumed within the housing at the lower end of the inclined wall, said curved wall being concentric with the axis of the vane, and means for swinging the vane within the housing to charge the siphon and open the inlet of the housing, said vane being movable past the upper end of the curved wall to a position where its end portion will project into the descending column of the short leg to form a water receiving pocket at the side toward the straight wall of the housing to effect a reseating of the vane at the end of the action of the siphon, and a water passage between its other side and the curved wall.

In testimony whereof I have affixed my signature, in presence of two witnesses.

HENRY H. GOVE.
